METHOD AND APPARATUS FOR BAKING
SOEDERBERG ANODES FOR ELECTROLY-
SIS CELLS

Claims priority, application Italy June 28, 1960
3 Claims. (Cl. 204—67)

The present invention relates to a method and apparatus for baking Soederberg anodes for electrolysis cells of the type used in the manufacture of aluminum, and more particularly to such method and apparatus wherein baking of the Soederberg anodes is carried out by means of alternating or direct current outside of the electrolytic cell itself.

Reference is made to the McGraw-Hill Encyclopedia of Science and Technology, 1960, vol. I, pages 290-294, for a discussion of Soederberg electrodes and prior art methods of their manufacture. Reference is also made to copending application Serial No. 119,465 of Landucci, filed June 26, 1961, and Serial No. 119,466 of Frerotti et. al., filed June 26, 1961.

As is well known, Soederberg self-baking anodes are widely employed in the industry in order to lead the current to the electrolyte of electrolytic cells, and such anodes are substantially constituted by a sheet-metal jacket whose horizontal cross section corresponds to the anode section. In the customary method of manufacture, a paste-like material composed of coal and pitch in definite proportions is charged into the sheet-metal jacket, and electric current is passed through the paste-like material by means of metallic rods, called "stubs," which penetrate into the paste-like material. This paste-like material is then baked by the heat of the cell, so that when the anode electrode is progressively lowered as it is consumed during the electrolysis, the lower part of the anode, on contact with the electrolytic bath, becomes hard-baked, which is the best condition for the anode leading the electric current to the interpolar zone and the best condition for the anode to take a part in the electrolytic reduction of alumina (Al_2O_3) in the production of metallic aluminum.

When a new electrolytic cell is started up, the electrode must be previously baked. Such baking is customarily carried out by lowering the anode into the cavity formed by the cathodic lining of the electrolytic cell, until the anode rests on the carbonaceous bottom, upon a previously interposed bed of powdered coal. The stubs or metallic rods are kept at the desired height by means of previously baked coal shims or cylinders. According to this known method, the lower part of the electrode is contained within a sheet-iron tray or container, whose task it is to contain the coal and pitch mixture or paste in its fluid phase during the baking operation. In such customary method of baking the anodes, the direct current utilized is conveyed to the electrode through the same circuit from which the electrolytic cell is subsequently fed for the electrolysis operation. Such direct-current baking, i.e., carried out "in situ," exhibits a number of drawbacks, which may be summarized as follows:

Production lags occur, occasioned from the period of baking time required which cannot be accelerated beyond a certain limit without danger of impairing the cathodic bottom, thus tying up the electrode cell and its electrolysis circuit when it might otherwise be used for electrolytic production. For the same reason, a greater labor burden is required. Furthermore, excessive smoke is released in the room containing the cells during such baking in

situ. Such prior art method also incurs localized electric and thermal stresses in the cathodic bottom with a resulting shorter life of the bottom and a concentration of electrical current.

5 The above-mentioned drawbacks are eliminated when the baking operation is carried out according to the present invention. According to the invention, the Soederberg anode, instead of being prepared and baked on the cell itself, is prepared and baked in separate apparatus or 10 baking rooms which are removed from the cell. Either alternating or direct current may be used, and the baking is carried out in a separate resistor furnace, the anode being formed from fresh electrodic paste. The apparatus comprises a container base of insulating masonry, a metallic tray for containing the fresh electrodic paste, and cross beams and contact stubs are provided for the electrical and mechanical connection of the electrode.

In the accompanying drawings:

FIG. 1 represents an elevation view partially in section 20 of a baking apparatus according to the invention;

FIG. 2 is a plan view of the apparatus according to FIG. 1;

FIG. 3 is a longitudinal section of the tray of FIG. 1; and

25 FIG. 4 is a transverse cross section through the detail of FIG. 3.

The baking room and apparatus according to the invention, as shown in the accompanying drawings, comprises essentially a container base *a* made up of insulating 30 masonry, an electric transformer *b* of variable ratio, a cross beam *c* supported by trestles or frame structure *d*, bus bars *e* for conveying the electric current from the transformer *b* to the baking apparatus, and clamps *f* for fastening the stubs or metallic rods *g* to the cross beam 35 *c* and bus bars *e*.

The following procedure is preferably adopted for carrying out the baking operation. A sheet-metal tray *h* (FIG. 3) is provided, having a horizontal cross section corresponding to the section of the electrode to be produced, and the tray *h* is arranged within the empty space in the base of the container *a*. Inert insulating powder *i*, for example alumina (Al_2O_3), is interposed between the tray *h* and the insulating masonry of the container base *a*.

45 The longitudinal portion of tray *h* is insulated toward the inside by means of sheets of insulating material *m*, such as asbestos board, as shown in the longitudinal section of FIG. 3 and the transverse cross section of FIG. 4.

50 The stubs *g*, fastened to clamping lugs *f*, are arranged at the desired height by interposing small cylinders *l* of coal or other carbonaceous material between the lower end of the stubs and the tray *h*. The clamping lugs *f* are set up in the precise position corresponding to that of the anodic terminal clamps of the electrolysis cell. The tray *h* is then filled with fresh electrodic paste. Current, either direct or alternating, is conveyed to the paste mixture, starting with the lowest current values and increasing the current gradually as the baking operation proceeds.

55 The current is transmitted to the stubs of the longitudinal portion of the electrode. Consequently, the current enters from these stubs, passes into the carbon-like mass of the electrode paste, and leaves from the stubs of the other longitudinal side of the electrode, as shown in FIG. 2.

60 The arrows show the direction of the current travel. The insulating sheets *m* aim at preventing a current short circuit through the tray *h*.

In order to further increase the capacity of the tray *h*, a small jacket *n* may be provided (FIGS. 1, 3 and 4) 65 which can be opened into two halves, as shown in FIG. 4. The jacket *n* is clamped around the tray sides in order to

obtain a heightening structure, which is removable from the sides of the tray *h*.

When the baking operation is completed, the jacket *n* may be readily taken apart and recovered for further use in baking of further anodes.

In place of the jacket *n*, the definitive anodic jacket to be eventually used in the electrolytic cell itself may be provided and used in forming the anode. A plurality of baking apparatuses may also be used, arranged in series with one another and fed from the same transformer.

Advantages of the described process and apparatus may be summarized as follows.

The invention provides speedy baking of the electrodes, since it is not restricted by the possibilities of impairing the cathodic bottom, as in the prior art methods. A reduced labor burden is incurred, and smoke from the baking operation is eliminated from the electrolytic cell workrooms. Mechanical and thermal stresses, caused by the prior art methods of baking of the cathodic bottom, are prevented. Opportunity is also provided for using alternating current, more readily carried and more easily transformable according to the variable loads in accordance with the specific requirements of the baking operation. A lower cost of baking is thus incurred, because of the lower cost of alternating current as compared with direct current.

In Table I are shown some typical characteristics of the operation carried out according to the invention by way of example.

Table I

Anodic element of	Baking duration, hours	Volt		Current (Amperes)		Consumed energy, kwh.	Temper. of electrode bottom mean value, °C.	Electrode height, cm.	Baking height mean value, cm.
		Minim- um, v.	Maxi- mum, v.	Initial, a.	Final, a.				
27 ka-----	72	6	10	3,000	10,000	3,200	700	60	30
64 ka-----	132	10	15	6,000	10,000	16,000	700	60	30

As shown in Table I, the two listed examples relate to tests with anodes of 27 ka. and 64 ka., respectively. The values relate to baking of the anodes in alternating current using an anode element equal to about half of a normal anode employed in the electrolytic furnace cell. In other words, the test was carried out on half-size anodes. Baking operations were performed with three elements at a time for anodes of 27 ka. and with two elements for anodes of 64 ka. employing a monphase 600 kva. transformer. When a transformer of higher power is used, the baking of the furnaces may be expedited by several days.

The values above listed in Table I apply in an analogous manner for direct-current operation as well as for alternating current.

It will be obvious to those skilled in the art, upon studying this disclosure, that the methods and apparatus according to our invention can be modified in various respects and hence may be embodied in processes and devices other than particularly illustrated and described herein, without departing from the essential features of our invention and within the scope of the claims annexed hereto.

We claim:

1. A method for baking carbonaceous electrodes for Soederberg electrolytic cells outside of the electrolytic cell, which comprises the steps of arranging on an electrically non-conducting refractory base a metal tray having a horizontal cross section corresponding to the section of the electrode to be produced, positioning on the inner bottom surface of said tray a layer of electrical insulating material, positioning within said tray and against the upper side of said layer insulating material a plurality of

electrical conducting members, placing within said tray in electrical contact with said members and in electrical contact with a portion of said tray a Soederberg-type carbonaceous paste, passing an electric current through said conducting members and through said tray and through said paste so that the paste itself forms a current-carrying path to produce a resistance-heating effect, gradually increasing said electric current from a relatively low value to a higher value until said paste acquires a hard baked layer, and transferring the paste mass thus baked to an electrolytic cell and connecting said mass as the anode thereof.

2. A process for starting an electrolytic furnace for the production of aluminum, comprising the steps of placing an electrically insulating refractory powder within a masonry container, positioning over said powder a metal tray having a cross section corresponding to the section of the electrode to be produced, positioning on the bottom and lower side-wall portions of said tray a layer of electrical insulating material, positioning within said tray and against said layer of insulating material a plurality of electrical conducting members, filling said tray with a Soederberg-type carbonaceous paste until said paste is in electrical contact with said members and with the upper side-wall portions of said tray, passing an electric current through said conducting members and through said paste so that the paste itself forms a current-carrying path to produce a resistance-heating effect, gradually increasing said electric current from a relatively low value to a higher

value until said paste acquires a hard baked layer, transferring the paste so baked to a Soederberg cell and connecting same as an electrode to the cell for the production of aluminum.

3. Apparatus for pre-baking of Soederberg-type electrodes, comprising a resistance furnace having a masonry container base of electrically insulating material, a metallic tray for containing fresh Soederberg carbonaceous electrode paste, and having a cross section corresponding to the electrode to be produced, insulating material forming an electrical insulating layer against only the lower side and bottom portion of the inner surface of said tray, contact stubs positioned within said tray with their bottoms against said layer and mutually spaced for transmitting electrical current along a generally horizontal path through the electrode paste so that the paste itself forms the current-carrying path so as to produce a resistance-heating effect, supporting structure for the contact stubs, and means for mechanically connecting and supporting the stubs to said supporting structure.
